The ornamental design for a data acquisition module, as shown and described.

DESCRIPTION

FIG. 1 is a perspective view taken from the front (left-hand end), top and right-hand side of a data acquisition module embodying the invention;

FIG. 2 is a perspective view taken from the back (right-hand end), bottom and right-hand side of the data acquisition module;

FIG. 3 is a front elevation of the data acquisition module; FIG. 4 is a rear elevation of the data acquisition module; FIG. 5 is a right side elevation of the data acquisition module;

FIG. 6 is a top plan view of the data acquisition module; FIG. 7 is a left side elevation of the data acquisition module; and,

FIG. 8 is a bottom plan view of the data acquisition module. The broken lines in the drawings depict portions of the data acquisition module that form no part of the claimed design.
